Attorney

UNITED STATES PATENT OFFICE

PAUL GEORGE JOHNSON, OF ERIE, PENNSYLVANIA, ASSIGNOR TO JOHNSON METAL PRODUCTS CO., OF ERIE, PENNSYLVANIA

SCREEN

Application filed January 21, 1930. Serial No. 422,428.

This invention relates to screens and has relation more particularly to an inside screen for use with the frame of a casement window and wherein the screen is provided with an opening through which is adapted to be disposed an operating member for a locking mechanism or the like when the sash or ventilator is closed.

The invention has for an object to provide a floating baffle carried by the screen and engaged with the screen for universal movement, said baffle being adapted to snugly engage a portion of the operating handle, said baffle operating to compensation for variations which may occur to assure an effective fly-tight job.

The invention consists in the details of construction and in the combination and arrangement of the several parts of my improved screen whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary elevational view of a screen having a baffle applied thereto constructed in accordance with an embodiment of the invention with an operating handle or the like disposed through said baffle;

Figure 2 is a sectional view taken substantially on the line 2—2 of Figure 1;

Figure 3 is a view in rear elevation of the screen as illustrated in Figure 1 with the features of the frame and operating handle or the like omitted.

The invention, as herein disclosed, is particularly adapted for use with a window structure of the type as embodied in the pending application of Theodore Johnson, Serial No. 358,389 filed April 26, 1929. The screen S is preferably supported in proper position with respect to the frame F in the same manner as set forth in such prior application although it is to be understood that

it is not desired to limit the present invention to any particular means of maintaining the screen in position.

The cloth of the screen S at a desired point thereon is provided with a relatively small opening 1, the portion of the cloth defining said opening being reinforced by the annular plates 2 and 3. The outer plate 2 has its inner marginal portion reverted, as at 4, said reverted portion 4 extending through the opening 1 and having clamping engagement with the inner plate 3 whereby the plates 2 and 3 are effectively maintained in position to afford a binding.

Arranged within the opening 1 is a baffle 5, herein disclosed as a continuous annular member, the interior diameter of which being such as to snugly receive the inner portion of the head 6 rotatably supported by a vertical member or stile 7 of the frame F and which head 6 operatively carries a locking disc or member 8 for engagement with a casement sash or ventilator to lock the same in fully closed position. The major diameter of the baffle 5 is less than the diameter of the opening 1 so that the baffle 5 is free to have independent and universal movement in any direction within said opening 1 in order to compensate or take care of any variations which may occur with respect to the axial centers of the baffle 5 and that portion of the head 6 within said baffle. The outer marginal portion of the baffle 5 is provided with an outstanding continuous annular flange 9 of a length to lap at all times the outer annular plate 2, thus assuring an effective fly-tight job.

The inner marginal portion of the baffle at points spaced circumferentially therearound is provided with the lugs 10 which are readily bent to lap the inner plate 3 whereby the baffle 5 after being applied is effectively held against displacement. These lugs 10 are of a length to maintain this lapping relation with respect to the plate 3 irrespective of the position of the baffle 5 with respect to the margin of the opening 1 in the screen.

It is believed to be understood that the head 6 constitutes a portion of an operating mem-

ber or handle for this disc or locking member 8 or may also be denoted as an actuator. From the foregoing description it is thought to be obvious that a screen constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A window screen cloth having an opening, and a floating baffle within said opening. 20
2. A window screen cloth having an opening, a baffle positioned within the opening of the cloth, the size of the baffle being such to permit the baffle to have independent universal movement within the opening, and means for retaining the baffle in applied position bridging at all times the space between the baffle and the margin of the opening in the cloth. 25
3. A window screen cloth having an opening, a baffle positioned within the opening of the cloth, the size of the baffle being such to permit the baffle to have independent universal movement within the opening, a continuous flange carried by the baffle and at all times lapping the marginal portion of the cloth defining the opening in the cloth. 30
4. A window screen cloth having an opening, a baffle positioned within the opening of the cloth, the size of the baffle being such to permit the baffle to have independent universal movement within the opening, a flange carried by the baffle and lapping at all times the face of the marginal portion of the cloth defining the opening, and means carried by the baffle lapping the opposite face of said marginal portion of the cloth and coacting with the flange to hold the baffle in applied position. 40
5. A window screen cloth having an opening and a floating baffle carried by the cloth, said baffle having an opening at all times in communication with the opening in the cloth. 50
6. A window screen cloth having an opening and a floating baffle carried by the cloth having an opening at all times within the field of the opening in the cloth. 55
7. The combination with a window screen cloth having an opening, a member insertable through said opening and a baffle surrounding said part when extended through the opening in the cloth to substantially close the space between said part and the margin of the wire cloth defining the opening thereof. 60
8. A window screen cloth having an open-

ing, a floating baffle carried by the cloth and coacting with the opening.

9. A window screen cloth having an opening, a baffle associated with said opening, and means for retaining the baffle in applied position upon the cloth, said means allowing the baffle to have universal movement. 70

In testimony whereof I hereunto affix my signature.

PAUL GEORGE JOHNSON.
